UNITED STATES PATENT OFFICE.

WILLIAM STENDER, OF MILWAUKEE, WISCONSIN.

ANNEALING-OVEN.

1,322,735.

Specification of Letters Patent. Patented Nov. 25, 1919.

Application filed April 10, 1918. Serial No. 227,685.

To all whom it may concern:

Be it known that I, WILLIAM STENDER, a citizen of the United States, and resident of Milwaukee, in the county of Milwaukee 5 and State of Wisconsin, have invented certain new and useful Improvements in Annealing-Ovens; and I do hereby declare that the following is a full, clear, and exact description thereof.

10 The present invention consists in novel and useful improvements in ovens in which bottles or the like may be annealed, the same being somewhat similar to the type of oven illustrated in United States Patent No. 15 1,247,890 which was issued to me on November 27, 1917.

In that patent means is illustrated for continuously moving an annealing bed, on which the articles to be treated are disposed, 20 through an oven, the articles, however, being only intermittently projected from the mechanism by which they are fed into the oven. The present invention is an improvement on this structure inasmuch as the annealing bed is only intermittently moved 25 through the oven, it being stationary while the bottles or the other articles are moved thereonto from the article receiving member.

This invention also contemplates a very 30 simply constructed, yet efficient means for synchronously actuating the article receiving member and the annealing bed on which the articles are projected after being received by said member.

35 An additional object is to provide an improved sweep for moving the articles from the article receiving member onto the annealing bed.

A still further object is to provide means 40 for readily disconnecting the endmost platform of the series of platforms forming the annealing bed after the same has been completely passed through the oven.

With such general objects in view the invention consists in certain novel features of construction, combination and arrangement of parts which will be hereinafter more particularly described and claimed and shown in the drawings, in which:

50 Figure 1 is a vertical sectional view through an annealing oven, said section being taken approximately on the plane of the line 1—1 of Fig. 2.

Fig. 2 is a detail horizontal section on the 55 plane of the line 2—2 of Fig. 1.

Fig. 3 is a plan view of the receiving end of the oven.

Fig. 4 is an enlarged detail section on the line 4—4 of Fig. 3, and

Fig. 5 is a detail section taken substantially on the line 5—5 of Fig. 1.

In the drawings wherein similar reference characters denote like parts throughout the several views, the numeral 1 indicates the opposite side walls of an annealing oven 65 having a bottom 2, a front wall 3, and a top wall 4, the latter having its front end terminated short of the ends of the side walls and end wall 3. The space at the front end of the oven which is not protected by the end 70 wall 3 (which is only about one-half the height of the side walls 1) and the top wall 4 is closed by a horizontal metallic cover plate 5 and a hood 6, the former being stationary and forming a journal plate as will 75 be hereinafter more particularly explained, while the latter is hinged at one side to provide a door whereby access may be had to the front end of the oven.

Positioned within the oven and extending 80 from the front wall 3 to a point spaced from the rear end and at approximately the level of the top of the former is a horizontal supporting floor 7. This floor has a trio of longitudinally extending parallel channel iron 85 tracks 8 and 9 in which rollers 10 and 11 respectively are adapted to run, said rollers being journalled carried by platforms 12 detachably connected together to provide an annealing bed. From the drawings it will 90 be noted that the track 9 is disposed centrally of the floor 7 between the outer tracks 8, and also that the rollers 11 that engage the first mentioned track are journalled in rack bars 13 secured to the platforms 12 95 (see particularly Fig. 5).

Said rack bars 13 coöperate with a pinion 14 secured on the upper end of a vertical shaft 15, whereby upon rotation of the latter the annealing bed will be shifted longitudinally through the oven. Any preferred means may be employed for performing the rotation of the shaft 15, but it has been found most desirable to use an electric motor M and connect the same thereto by means 105 of suitable gearing or the like indicated broadly in Fig. 1 by the numeral 16. The teeth of the racks 13 are retained in engagement with those of the pinion 14 by means of an idle pulley wheel 17 mounted on the 110

floor 7 on the opposite side of the track 9 to which the shaft 15 is disposed, said pulley wheel being annularly grooved for the reception of a rib 18 formed on the rack bar 13.

5 Bottles or the like B are fed into the oven preferably directly from a molding machine (not shown) through a chute 19. The inner end of the chute terminates adjacent the periphery of an annular article receiving member 20 and also at the end of a stationary horizontally disposed article supporting plate 21, the same being mounted directly over the annealing bed. This plate is semi-circular and conforms to the curvature of 10 the periphery of the article receiving member 20. The latter element has a plurality of pockets formed in its periphery by means of a plurality of spaced peripheral fingers 22 whose ends are curved laterally in the 15 direction of rotative movement of the member. It will thus be seen that as such article receiving member is rotated in the proper direction the pockets will be successively brought into position to receive a 20 bottle or other article of the plurality of such articles fed into the oven through the chute 19.

The rate of feeding of the bottles through the chute determines the speed with which 25 the successive pockets are brought into co-action with the end of the chute. In carrying out such an arrangement I provide the article receiving member 20 with an upright shaft 23 of sufficient length to project 30 upwardly to be journally mounted in the plate 5, a ratchet wheel 24 secured to the upper end of the shaft 23, and a reciprocative rod 25 which carries a pivoted dog 26 for engagement with the teeth of the ratchet. 35 The rod 25 is the continuation of a piston rod which is movable in a fluid pressure cylinder 27, motive fluid being supplied thereto from any suitable source through pipes 28 and 29 and a valve 30 that connects 40 the same. The valve 30 is positioned adjacent the chute 19 and has an operating arm 31 of sufficient length to project thereinto so that as each bottle B is moved thereinto it will be engaged thereby. The motive fluid 45 moves the rod 25 in one direction only, it being returned by an expansile spring 32. Thus in view of the successive engagement 50 of the arm 31 by the bottles or the like passing through the chute 19, the article receiving member 20 will be rotated step by step in the same direction.

After the member 20 has been actuated a predetermined number of steps, or in other words after a predetermined number of articles have been received in the pockets of the member, means is actuated for shifting the articles from their respective pockets and off the supporting plate 21 onto the annealing bed 12. As in the structure illustrated in the above mentioned patent, a

sweep arm 33 is provided for this movement of the articles from the article receiving member. In the present invention, however, this arm is in the form of an arcuate bar supported at one end by means of a rod 33 70 that depends from the plate 5 to which it is pivoted by a link 34. The intermediate portion of the arm is in turn pivotally connected with one end of a crank 35 that projects from the lower end of a vertical shaft 36, the 75 upper end of the latter being also journaled in the plate 5 and preferably projecting therethrough.

The upper end of the shaft 36 which is extended above the plate 5 has a pinion 37 80 secured thereto, the teeth of which are meshed with the teeth of a longitudinally movable rack 38, the latter being carried in a guide 39. A second fluid cylinder 40 is mounted on the plate 5 adjacent the first 85 mentioned cylinder 27 and has a piston therein, to the rod 41 of which one end of the rack bar 38 is secured. Motive fluid for this cylinder 40 is supplied through the pipe 29 and through additional pipes 42 90 and 43, the last two mentioned pipes being connected together through a valve 44.

Inasmuch as the sweep arm 33 is only to be operated intermittently, it being at other times in retracted position the motive fluid 95 is only allowed to pass into the cylinder 40 when the article receiving member has been moved a predetermined number of steps. Therefore in order that the movement of the latter may control the movement of the 100 sweep arm, I provide a gear wheel 45 for engagement by the teeth of the ratchet 24, said gear wheel having a cam 46 for co-action with an operating arm 47 of the valve 44. This valve is normally held in closed 105 position by a spring 48.

When motive fluid is permitted to enter the cylinder 40 it is obvious that the rack bar 38 will be moved longitudinally and away from said cylinder. Such movement is taken advantage of to control the operation of the motor M which drives the annealing bed through the oven. That is to say a switch formed of contacts 49 and 50, which are normally spaced apart, is placed in the 110 motor circuit. When the rack bar 38 has reached its limit of movement away from the cylinder 40 its end will strike the movable switch contact 50 and cause it to engage the other contact 49 and complete the motor 115 circuit. Upon the release of the motive fluid in the cylinder 40 an expansile spring 51 therein will retract the piston and therefore the rack bar. The switch is thereupon again opened and the operation of the motor 120 M stopped.

After the platforms of the annealing bed have been moved completely through the oven by the intermittent operation of the motor M, the end-most platforms are suc- 125 130

cessively disconnected from the next adjacent ones and removed from the bed. The opposite ends of each platform are respectively provided with one or more vertically 5 extended studs 52 and a corresponding number of eyes 53, it being obvious that the studs of one platform coöperate with the eyes of the next adjacent platform. In this manner platforms may be removed from one 10 end of the annealing bed and connected with the other end so that the passage of the same through the oven will be unbroken.

The invention includes means for readily disconnecting the end-most platform after 15 it has passed through the oven, and in carrying out this object a floor section 54 is pivoted at its outer end as at 55 at the rear end of the floor section and is disposed close to the rear end of the floor 7; further- 20 more the floor section has tracks 56 which align with the tracks on the floor 7. Inasmuch as the ends of the platforms carrying the eyes 53 are first inserted into the oven through the front end thereof, it will be 25 seen that as the inner end of the end-most platform, designated in Fig. 1 as 12^a, is brought over the rear end of the floor 7, the same may be readily disconnected from the next adjacent platform 12 by depressing 30 or lowering the inner end of the floor section 54. A retaining arm 57 fixed to a horizontal shaft 58 in turn journaled in a standard 59 is used for holding the floor section in the same horizontal plane as the floor 7. 35 But, when it is desired to depress the floor section the shaft 58 is rocked by means of a handle lever 60 on the outer side of the oven.

Briefly the operation of the article feeding and conveying mechanism is as follows:—Bottles or the like B are shoved into 40 the chute in any preferred manner until the inner-most one is positioned in the adjacent pocket of the article receiving member 20. Therefore as each successive bottle is moved into engagement with the operating arm 31 of the valve 30, the latter is 45 opened to permit motive fluid to pass into the cylinder 27, said valve remaining open a sufficient length of time to allow the article receiving member to be rotated a 50 distance to bring the next pocket into alignment with the inner end of the chute 19. Upon the closing of the valve 30 and the release of the motive fluid in the cylinder 55 27, the spring 32 retracts the rod 25 and the spring pressed pawl 26 so that the latter may take a new grip in the teeth of the ratchet 24. It will be noted that each partial revolution of the ratchet will cause similar 60 movement of the gear wheel 45.

The size of the gear wheel 45 is such that after a predetermined number of pockets of the article receiving member have been filled, the cam 46 will be brought into 65 engagement with the operating arm 43 to

open the valve 44. This permits motive fluid to actuate the rack bar 38 as hereinbefore explained, such movement causing the projection of the sweep arm and the removal of the articles from the article receiving member onto the annealing bed. Immediately after the sweep arm has become effective and the bottles or the like disposed on the bed, the latter is moved a predetermined distance through the oven by the motor M. 70 After the cam 46 no longer engages the operating arm 43 the rack bar will be retracted and the movement of the annealing bed stopped. In this manner the successive rows of articles deposited on the bed will 75 be relatively close together.

Various minor changes may be made in the form and proportion of various parts of the invention without departing from or sacrificing any of the advantages thereof, as for 80 instance the parts may be modified to accommodate articles other than those of bottle shape.

I claim:—

1. In an apparatus of the class described, 90 a bed, an article receiving member, means for delivering articles to the article receiving member, and means for ejecting articles from the article receiving member onto the bed including a shaft, a sweep arm secured to one end of the shaft adjacent the article receiving member, a pinion on the shaft, a rack engaged with the pinion, and means for moving the rack when a predetermined number of articles have been delivered to 100 the article receiving member.

2. In an apparatus of the class described, 105 a shiftable bed, an article receiving member, means for delivering articles to the article receiving member, and means for ejecting the articles from the article receiving member including a shaft, a sweep arm secured to one end of the shaft adjacent the article receiving member, a pinion on the shaft, a rack engaged with the pinion, 110 means for moving the rack when a predetermined number of articles have been delivered to the article receiving member, and means operable by a predetermined movement of the rack for shifting the bed. 115

3. In an apparatus of the class described, 120 a bed, an article receiving member, means for delivering articles to the article receiving member, and means for ejecting the articles from the article receiving member onto the bed including a support, a sweep arm, a link pivotally connected with one end of the sweep arm and the support, a shaft, a crank extending from the shaft and pivoted to the sweep arm intermediate its ends, and 125 means for rocking the shaft.

4. In an annealing oven, a main stationary supporting floor, a depressible floor section at one end of the supporting floor, a bed movable over the floor and floor section 130

and comprising a plurality of separable platforms, and means for lowering the floor section when one of the separable platforms is thereover to readily separate the same from the next adjacent platform.

5. In an annealing oven, a main stationary supporting floor, a depressible floor section pivoted at its outer end, a bed movable over the floor and floor section and comprising a plurality of separable platforms, and means for lowering the inner end of the floor section to readily separate the outermost platform from the next adjacent one.

6. In an annealing oven, a main stationary supporting floor, a depressible floor section at one end of the supporting floor, a

bed movable over the floor and floor section and comprising a plurality of separable platforms each having an eye at one end and a stud at the other for co-action with the corresponding eyes and studs on the adjacent platforms, and means for lowering the floor section when one of the separable platforms is thereover to readily disconnect the stud thereof from the eye of the next adjacent platform.

In testimony that I claim the foregoing I have hereunto set my hand at Milwaukee, in the county of Milwaukee, and State of Wisconsin.

WILLIAM STENDER.
